CLAIM

I claim the ornamental design for an RV conversion handle, as shown and described.

DESCRIPTION

FIG. 1 is a perspective view of an RV conversion handle; FIG. 2 is a perspective view thereof shown in environmental use;

FIG. 3 is a side view of FIG. 1;

FIG. 4 is a front view thereof; and,

FIG. 5 is a top view thereof.

The broken lines are for environmental purposes only and form no part of the claimed design.
